15 INVENTOR,

Walter S. Jarboe,
by George H. Christie
Atty.

UNITED STATES PATENT OFFICE.

WALTER S. JARBOE, OF ALLEGHENY, ASSIGNOR TO THE PITTSBURG MOP WRINGER COMPANY, OF PITTSBURG, PENNSYLVANIA.

MOP-WRINGER.

SPECIFICATION forming part of Letters Patent No. 447,732, dated March 3, 1891.

Application filed December 1, 1890. Serial No. 373,186. (No model.)

To all whom it may concern:

Be it known that I, WALTER S. JARBOE, a citizen of the United States, residing at Allegheny, in the county of Allegheny and State of Pennsylvania, have invented or discovered a certain new and useful Improvement in Mop-Wringers, of which improvement the following is a specification.

The object of my invention is to provide a 10 mop-wringer of simple and inexpensive construction, having its working parts arranged so as to avoid obstructing the inside of a pail, and adapted to convenient and effective operation in wringing out a mop.

15 To this end my invention, generally stated, consists in the combination, with a pail, of a pair of vibrating wringing-rolls, a pair of transversely swinging clamping-bails actuated by one of said rolls, and springs by which 20 the rolls are coupled to a pivoted treadle.

The improvement claimed is hereinafter fully set forth.

In the accompanying drawings, Figure 1 is 25 an isometrical view of a mop-wringer embodying my invention, and Fig. 2 a vertical longitudinal section through the same.

In the practice of my invention I provide a pail or water-receptacle 1, which is preferably 30 of sheet metal, and, as shown, of rectangular form. A frame or rim 2 is connected to the top of the pail, and two pairs of bearings 3 are connected to said frame, one pair being adjacent to each end thereof. Two wringing-rolls 4 are fitted to vibrate toward and from each 35 other above the pail, each roll being connected to the upper ends of a pair of links 6, the lower ends of which are provided with journals 7, mounted in the bearings 3. A clamping-bail 8, which is formed of wire bent 40 preferably into substantially rectangular form, is journaled in a bearing 9 on each side of the frame between the bearings 3, each bail having an arm 10 projecting upwardly from one of its journals. A treadle 45 composed of two arms 11, located on opposite sides of the pail and connected to a foot-plate 12, extending transversely thereto near one of its ends, is pivoted to vertical standards or extensions 13, formed on a pair of 50 removable base-bars 14, which fit against the

sides of the pail at the bottom thereof, and are connected by transverse bolts 15, having nuts 16 on their ends, by which the bars are drawn and held closely against the sides of the pail. The supporting-links 6 of each of 55 the wringing-rolls 4 are connected by springs 17 with the treadle-arms 11, the tension of the springs maintaining the parts normally in the positions shown in Fig. 1 and in full lines in Fig. 2. Fingers 18 are secured to one 60 of the pairs of links 6 in such position as to abut against the arms 10 of the clamping-bails 8 when the rolls 4 are moved inwardly or toward each other by downward movement of the treadle, the pressure of said fingers 65 swinging the bails into horizontal position when the rolls are brought near each other.

In operation the mop is placed in the pail and the treadle depressed by the foot of the operator, thereby bringing the rolls 4 into 70 contact and swinging the clamping-bails 8 into horizontal position. The mop being then drawn out between the wringing-rolls and clamping-bails under compression from both 75 pairs of members the water will be thoroughly driven out, and upon the relief of pressure upon the treadle the springs return the rolls and bails to normal position in readiness for another operation.

I claim as my invention and desire to secure by Letters Patent—

1. The combination, with a pail, of a pair of vibrating wringing-rolls, a pair of clamping-bails swinging transversely to the rolls and actuated by one of said rolls, a pivoted 85 treadle, and springs coupling the rolls to said treadle, substantially as set forth.

2. The combination of a pail, a rim or top frame connected thereto, swinging links journaled in pairs in bearings on the rim, wringing-rolls connected to the free ends of said pairs of links, a pair of clamping-bails journaled on the rim at right angles to the wringing-rolls, a treadle pivoted on the pail, springs coupling said treadle with the links of the 95 wringing-rolls, and fingers connected to one pair of said rolls in position to abut against arms on the clamping-bails, substantially as set forth.

3. The combination of a pail, a pair of re- 100

movable base-bars, transverse bolts clamping
said base-bars against opposite sides of the
pail, a treadle pivoted to extensions on the
base-bars, a top frame or rim connected to
5 the pail, a pair of wringer-rolls fixed to links
journalized on the rim, and springs coupling
said links to the treadle, substantially as set
forth.

In testimony whereof I have hereunto set
my hand.

WALTER S. JARBOE.
